GOLF CLUB ATTACHMENT

Thomas W. Harrigan, 1709 Coral Gardens Drive,
Fort Lauderdale, Fla.

Filed Oct. 11, 1962, Ser. No. 72,079

Term of patent 3½ years

(Cl. D34—5)

FIG. 1

FIG. 2

FIG. 3

FIG. 4

The fragmentary broken line showing of a club head in FIGURE 5 is for illustrative purposes only.

I claim:

The ornamental design for a golf club attachment, as shown and described.
